CLAIM

The ornamental design for a wheel as shown and described.

DESCRIPTION

FIG. 1 is a perspective view taken from a front, top, right side of a wheel according to a first embodiment of our design;

FIG. 2 is a perspective view taken from a rear, top, left side thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a perspective view taken from a front, top, right side of a wheel according to a second embodiment of our design;

FIG. 10 is a perspective view taken from a rear, top, left side thereof;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top plan view thereof; and,

FIG. 16 is a bottom plan view thereof.
